UNITED STATES PATENT OFFICE.

EMIL DIETZE, OF BROOKLYN, NEW YORK.

BOX-STRAP-FASTENING MEANS.

1,348,271.

Specification of Letters Patent.

Patented Aug. 3, 1920.

Application filed January 27, 1920. Serial No. 354,405.

To all whom it may concern:

Be it known that I, EMIL DIETZE, a citizen of the United States, residing at Brooklyn, in the county of Kings and State of New York, have invented certain new and useful Improvements in Box-Strap-Fastening Means; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to an improved box-strap fastening means or seal; and the invention has reference, more particularly, to a novel construction of fastening seal member which is adapted to securely fasten a metallic strap or tie in place around a box or packing case, without necessity of employing nails, or other additional fastening means.

Other objects of the present invention, not at this time more particularly enumerated, will be clearly understood from the following detailed description of the same.

With the various objects of the present invention in view, the same consists, primarily, in the novel construction of fastening seal member adapted to engage and anchor in fastening relation to a packing-case, or the like, the respective ends of an embracing reinforcing strap or tie herein-after set forth; and the invention consists, furthermore, in the novel arrangements and combinations of the parts of the device, as well as in the details of the construction thereof, all of which will be hereinafter more fully described and claimed.

The invention is clearly illustrated in the accompanying drawings, in which:

Figure 1 is a perspective view of one end of a packing casing having applied thereto a reinforcing strap or tie anchored and secured in place by the novel construction of fastening seal member made according to and embodying the principles of my present invention.

Fig. 2 is a plan view of one form of my novel seal member; Fig. 3 is a side edge view of the same; Fig. 4 is an end elevation of the same, looking toward the left in Fig. 3; Fig. 5 is a detail longitudinal section of the novel seal member operatively related

to a strap or tie embracing a box or case, and ready to be driven home into operative anchoring and securing relation to said strap or tie; and Fig. 6 is a view similar to that shown in said Fig. 5 after the seal member has been driven into complete operative anchoring and securing relation to said strap or tie.

Fig. 7 is a plan view of a modified form of my novel seal member; Fig. 8 is a side edge view of the same; Fig. 9 is an end elevation of the same, looking toward the left in said Fig. 8; and Fig. 10 is a detail longitudinal section of the same operatively related to a strap or tie embracing a box or case, and driven into complete operative anchoring and securing relation to said strap or tie.

Similar characters of reference are employed in all of the hereinabove described views, to indicate corresponding parts.

Referring now to said drawings, the reference-character 1 indicates a packing case around which is arranged one or more reinforcing straps 2, preferably made of band metal. Said strap 2 is arranged to surround the packing case so as to extend over four sides thereof, in the usual manner.

The means for securing the strap 2 in the above described embracing relation to the packing case 1 comprises a novel construction of seal member, the preferred form of which is illustrated in Figs. 1 to 6 inclusive of the drawings. This seal member 90 comprises a metallic body bent downwardly at its rear end or base to produce a normally perpendicular rear tongue or stirrup portion 3, from the upper end of which extends an initially upwardly and forwardly inclined main body 4. Formed in said body 4, at the junction thereof with the tongue or stirrup portion 3, is a laterally extending slot or stirrup opening 5. Formed in connection with and struck downwardly out of said body 4, intermediate its free end and said stirrup opening 5, is a fastening lug 6, which is initially perpendicular or parallel to said tongue or stirrup portion 3. Said fastening lug 6 is so related to said body 4 105 as to be disposed in a transversely oblique relation thereto. Said fastening lug 6 is substantially rectangular in outline, the same having a square lower edge 7 terminating at one side or corner of its lower free end, however, in a downwardly projected sharpened spur or piercing point 8.

110

In operatively relating said novel seal member, so constructed, to the strap 2, one end 9 of the latter is passed over the outer face of the tongue or stirrup portion 3, and 5 then threaded or passed through the slot or stirrup opening 5, the extremity 10 of the end 9 being then turned downwardly across the inner face of the tongue or stirrup portion 3 and registered behind the outer portion 10 of said end 9. The novel seal member, with one end of the strap 2 so attached thereto, is then placed against a corner of the packing case 1, with the tongue or stirrup portion 3 extending vertically downward 15 from the corner edge 11 of the case and against its forward side or face, so that the extremity 10 of the strap end 9 lies between the latter and said forward side or face of said packing case. The main body 4 inclines 20 upwardly from said corner edge 11 above the upper side or face of the packing case, with the fastening lug 6 and its spur 8 directed perpendicularly downward toward said upper side or face of the packing case. 25 The strap 2 is then passed downward over the forward face of the packing case 1, underneath and across the bottom face thereof, upwardly across the rear face thereof, and thence forwardly across the upper face 30 thereof, the opposite or free end 12 of the strap 2 being passed beneath the fastening lug 6 and its spur 8, and then threaded or passed outwardly through the slot or stirrup opening 5. When the seal member is thus 35 initially assembled relative to the strap 2 and packing case 1 (as shown in Fig. 5 of the drawings) it is ready to be operated upon to drive or force the same into operative securing relation to said strap and fastening case, this operation being easily accomplished by striking the upwardly inclined body 4 smart downwardly forcing or driving blows with any suitable tool or hammering means. The blows so applied 40 bend and flatten down the main body 4 from its initially upwardly inclined position, so that the same lies flat upon the strap end 12, and in substantially right angled disposition relative to said tongue or stirrup portion 3, 45 the body 4 bending from the point of its junction with said tongue or stirrup portion as a fulcrum point. In thus flattening down the body 4 the fastening lug 6 is caused to penetrate through the strap end 12, and is 50 then driven into the wood body of the packing case 1, the sharpened spur 8 serving to initially pierce the strap end so that the end of the fastening lug 6 may more easily shear therethrough, and at the same time 55 turn or curve downwardly the edges 13 bounding the opening thus made in the body of the strap end by the fastening lug 6. Since that portion of the body 4 in which the fastening lug is formed, describes an 60 65 arc in swinging downward from the ful-

crum point above mentioned, and since the fastening lug 6 is initially perpendicular, the tendency of the flattening down movement imparted to the body 4 is to cause the fastening lug 6, as it penetrates the wood 70 of the case 1, to assume a forward slant or inclination (as shown in Fig. 6 of the drawings,) thus positioning the same in the wood so that its resistance to accidental withdrawal is greatly increased. As the fastening lug 6 passes through the body of the strap 2, its transversely oblique face is presented in opposition to the pulling strain of the stretched strap, so that any tendency to shear through the strap tends to crowd the 75 sheared portion toward the angular corner X, jamming the same therein so as to quickly obstruct and prevent any continued shearing or tearing action which would eventually release the strap end from fastened position, or slacken the same from the desired tautly stretched relation to the packing case. 80 85

After the strap is thus sealed, locked and secured in the desired embracing and binding relation to the packing case, the outwardly projecting portion of the free end 12, where the same projects through the stirrup opening 5, is cut off close to the tongue or stirrup portion 3 (as shown in Figs. 1 and 95 6,) so that a neat appearance results.

Referring now to Figs. 7 to 10 inclusive of the drawings, I have shown therein, a modified form of my novel strap seal member, which embodies the essential principles 100 of my invention. This modified form of seal member comprises a body portion bent downward at its rear end to provide the normally perpendicular stirrup portion 3, together with the stirrup opening 5, and the 105 initially upwardly and forwardly inclined main body 4. In this modification the main body 4 possesses forwardly converging side edges, so that the same terminates at its forward or free end in a downwardly projecting and initially perpendicular sharpened spur 14. The body of said spur 14 is formed in concavo-convex shape to provide at its rear side a laterally convex face 15. In this modified construction said spur 14 110 takes the place of the fastening lug 6 of the first described construction. The method of associating and fastening the modified form of seal member is substantially the same as already above described in connection with the first described construction. When the main body 4 is flattened down, the spur 14 passes through the body of the strap 2 so that the same penetrates 115 slantingly into the wood of the packing case 1, as shown in Fig. 10 of the drawings, thus positioning the same so that it offers a considerable resistance to accidental withdrawal therefrom. The convex face 15 is presented in opposition to the pulling strain 120 125 130

of the stretched strap, thereby eliminating at such point sharp edges in engagement with the strap, which under the strain of the pull thereon, might easily cause the body 5 of the strap to be sheared through, and slackened from the case, and possibly wholly disconnected from the seal member. Said convex face, if any tearing of the strap body does occur, tends to curl downwardly the 10 marginal edges of the tear, so as to force the same downwardly into the wood of the case, and thereby immediately opposing additional obstruction to the pulling strain upon the strap.

15 I am aware that some changes may be made in the several arrangements and combinations of the devices and parts of my novel seal member, as well as in the details of the construction of the same, without departing from the scope of my invention as above described, and as defined in the following claims. Hence, I do not limit my invention to the exact arrangements and combinations of the devices and parts as 20 set forth in the above specification, nor do I confine myself to the exact details of the construction of said parts as illustrated in the accompanying drawings.

I claim:—

30 1. A box strap seal, comprising a metallic member formed to provide a vertical stirrup portion having a stirrup opening through which one end of a box strap may be passed and doubled back upon itself to attach the same to said seal, and an initially upwardly and forwardly inclined main body extending from the upper end of said stirrup portion having integrally formed in connection therewith an initially perpendicular down- 35 wardly projecting portion adapted to be driven through the opposite end of said box strap positioned beneath said main body by flattening down the latter thereon.

40 2. A box strap seal to be arranged with an angular edge of a box or the like, com-

prising a metallic member formed to provide a vertical stirrup portion having a stirrup opening through which one end of a box strap may be passed and doubled back upon itself to attach the same to said seal, an initially upwardly and forwardly inclined main body extending from the upper end of said stirrup portion, and an integral initially perpendicular fastening lug struck downwardly out of said main body, said 50 fastening lug having at its lower free end a sharpened spur, said fastening lug and its spur being adapted to be driven through the opposite end of said box strap positioned beneath said main body by flattening down 55 the latter thereon.

3. A box strap seal to be arranged with an angular edge of a box or the like, comprising a metallic member formed to provide a vertical stirrup portion having a 60 stirrup opening through which one end of a box strap may be passed and doubled back upon itself to attach the same to said seal, an initially upwardly and forwardly inclined main body extending from the upper 65 end of said stirrup portion, and an integral initially perpendicular fastening lug struck downwardly out of said main body, said fastening lug being substantially rectangular in shape and disposed in transversely oblique 70 relation to said main body, and a downwardly directed sharpened spur formed in connection with the free end of said fastening lug at one side thereof, said fastening lug and its spur being adapted to be driven 75 through the opposite end of said box strap positioned beneath said main body by flattening down the latter thereon.

In testimony, that I claim the invention set forth above I have hereunto set my hand 80 this 12th day of January, 1920.

EMIL DIETZE.
